UNITED STATES PATENT OFFICE.

JOHN L. BRYANT, OF HILSDALE, MICHIGAN.

DRILL.

SPECIFICATION forming part of Letters Patent No. 226,043, dated March 30, 1880.

Application filed November 15, 1879.

To all whom it may concern:

Be it known that I, JOHN L. BRYANT, of Hillsdale, in the county of Hillsdale and State of Michigan, have invented an Improvement 5 in Drills, of which the following is a specification.

The nature of this invention relates to a certain new and novel construction of a drill and frame, whereby the same can readily be applied to the article to be drilled.

The invention consists in the peculiar construction and combination of the various parts, all as more fully hereinafter set forth.

Referring to the drawings, Figure 1 is a perspective view. Fig. 2 is a vertical central section.

In the accompanying drawings, which form a part of this specification, A represents a suitable frame, the two portions of which are pivoted together, as at *a*. Through the head *A'* of the frame is tapped a hollow screw, *B*, upon the upper end of which is secured a hand-wheel, *C*.

D is a drill-stock placed through the hollow screw *B*, being held in place by a screw or pin, *b*, passing through the hand-wheel *C*.

and entering the channel *c* formed in the drill-stock. On the lower end of the drill-stock is secured a head, *d*, which receives the drill *E*, any suitable device being attached to the upper end to rotate it.

The lower ends of the frame *A* are provided with the flat bearing-surfaces *e*, and the two portions of the frame are secured in a closed position by means of a spring latch-bar, *F*.

By this construction of parts my device will be found adaptable to many points where the ordinary drill could not be used.

What I claim as my invention, and desire to secure by Letters Patent, is—

A drilling-machine wherein are combined the pivoted frame *A*, the hollow screw *B*, and the drill-stock *D*, held in place by pin *b*, passing through the hollow screw *B* and the hand-wheel, and the spring latch-bar *F*, all constructed and arranged substantially as and for the purposes set forth.

JOHN L. BRYANT.
